The ornamental design for a sprayer shroud, as shown and described.

DESCRIPTION

FIG. 1 is a perspective view of a sprayer shroud in accordance with the present invention;

FIG. 2 is a perspective view of the sprayer shroud of FIG. 1;

FIG. 3 is a right side view of the sprayer shroud of FIG. 1;

FIG. 4 is a top view of the sprayer shroud of FIG. 1;

FIG. 5 is a front view of the sprayer shroud of FIG. 1;

FIG. 6 is a rear view of the sprayer shroud of FIG. 1;

FIG. 7 is a bottom view of the sprayer shroud of FIG. 1;

FIG. 8 is a left side view of the sprayer shroud of FIG. 1;

FIG. 9 is a perspective view of another embodiment of sprayer shroud in accordance with the present invention;

FIG. 10 is a perspective view of the sprayer shroud of FIG. 9;

FIG. 11 is a right side view of the sprayer shroud of FIG. 9, the left side being a mirror image thereof;

FIG. 12 is a top view of the sprayer shroud of FIG. 9;

FIG. 13 is a front view of the sprayer shroud of FIG. 9; and,

FIG. 14 is a rear view of the sprayer shroud of FIG. 9.

The edges of the shaded areas represent the bounds of the claimed design. All broken lines represent portions of the sprayer shroud which are provided for illustrative purposes only and form no part of the claimed design.
